UNITED STATES PATENT OFFICE.

LYCURGUS BURNHAM, OF WOBURN, ASSIGNOR OF ONE-HALF TO WALTER L. FRENCH, OF BROCKTON, MASSACHUSETTS.

COMBINED CANE AND CAMP-STOOL.

SPECIFICATION forming part of Letters Patent No. 236,670, dated January 18, 1881.

Application filed July 2, 1880. (Model.)

To all whom it may concern:

Be it known that I, LYCURGUS BURNHAM, of Woburn, Massachusetts, have invented a new and useful Improvement in a Combined 5 Cane and Camp-Stool; and I hereby declare that the following specification and the accompanying drawing give a correct description of the same.

My improvement is supplementary to the 10 invention of D. B. Reynolds, patented August 14, 1877. The combined cane and camp-stool described in said patent consists of a knob or ball, which is the head of the cane, and three detachable lengths of wood or other suitable 15 material, which are fastened together end to end and to the knob to form the cane.

To form the camp-stool, the three lengths of the cane are first detached from each other and then screwed or otherwise inserted into suitable 20 holes in the knob, so as to form a tripod. Then into three or more other holes properly located in the knob are inserted standards, which serve to support a flexible seat.

My invention relates entirely to the knob or 25 head of the cane above mentioned, and my object is to construct the same so as to combine the three requisites of strength, lightness, and convenient size. The knob has heretofore been made of wood, which material is suitable 30 as to lightness, but has been found not sufficiently strong. It was considered impracticable to make it of metal, because a solid metallic ball, if large enough for a handle, would

be too heavy, and if made hollow the shell would necessarily be too thin to give sufficient 35 support to the legs and standards before mentioned.

The nature of my invention consists in making a hollow metallic knob of the proper size and weight, and furnishing the same with certain 40 internal projections or bosses to be described.

The figure represents the knob and part of the shaft of the cane, and also a partial vertical section of the knob, showing one of the 45 internal bosses.

The bosses B are cast in one piece with the shell A, and are so located that the holes C, made in the knob to receive the legs and standards, extend into the said bosses. Thus the 50 holes may be of sufficient depth to give adequate support to the legs and standards, and still the shell may be thin enough to give the required lightness.

What I claim is—

In a combined cane and camp-stool, composed essentially of a spherical head and a cane-body, formed in three sections, adapted to be coupled to the head to form a tripod, the hollow metallic ball A, having internal bosses, B, 60 arranged substantially as described, and for the purpose set forth.

LYCURGUS BURNHAM.
